ELECTRICAL COINCIDENTAL LOCKING
SYSTEMHorace D. Seelinger, Detroit, Mich., assignor to
General Motors Corporation, Detroit, Mich., a
corporation of Delaware

Application January 9, 1939, Serial No. 249,891

6 Claims. (Cl. 70—264)

The present invention relates to a coincidental locking system for closure devices, and is particularly adaptable to the doors of automotive vehicles.

5 The object of my invention is to provide a convenient means in which a plurality of latch devices may be set for locking at one station, each station of which is locked by a slight initial movement of the individual latch retracting means. Electrical mechanism for accomplishing this object may be used separately or the combination of both mechanical and electrical locking means may be used so that double protection may be obtained.

10 Figure 1 is a diagrammatic view of a plurality of locking mechanisms and the electrical circuit connections between them to provide a coincidental locking system.

15 Figure 2 is a detailed sectional view of a master locking mechanism used to control a plurality of similar dependent locking mechanisms.

20 Figure 3 is a similar view of the mechanism shown in Figure 2 with the parts shown in the locked position.

25 Figure 4 is a detailed sectional view showing an alternate form of master locking mechanism with mechanical means for rendering the outside latch retracting means ineffective in combination with electrical means for preventing 30 movement of the latch bolt.

Figure 5 is a sectional view taken on the line 5—5 of Figure 4 showing details of the latch bolt and lock bar structure.

35 Figure 6 is an enlarged sectional view taken on the line 6—6 of Figure 4 showing the linkage for operating the electrical switch mechanism.

Figure 7 is an enlarged fragmentary view of a detail of Figure 4 with parts broken away, the section being taken on the line 7—7 of Figure 6.

40 Figure 8 is a sectional view taken on the line 8—8 of Figure 4 showing the lock bar in its unlocked position with reference to the latch bolt. The locked position of the bar is shown by the broken line.

45 Figure 9 is a sectional detailed view of further modification showing a dependent locking mechanism in which the latch retracting mechanism is rendered ineffective by either electrical means controlled remotely by a master latching mechanism or directly by mechanical means.

50 The locking mechanism shown in Figure 2 comprises a latch bolt 1 slidably mounted on a frame 3 by means of a bearing 5 at one end and on the other by means of a stud 7 which is fixed to the frame 3 and extends through a

slot 9 in the latch bolt 1. A bow spring 11, one end of which is looped around the stud 7 and the other end extending into an opening 12 in the latch bolt 1, is provided to project the latch. A shaft 13 rotatably mounted in the frame 3 has 5 the usual outside handle (not shown) fixed to one end and a collar 15 fixed to the shaft 13 at its inner end. The collar 15 has an integral pawl 17 and a sector portion 19 provided with a recess 21 in which an insulating segment 23 is 10 fixed. The pawl 17 bears against a downward extending projection 25 on the latch bolt 1 and when moved counterclockwise retracts the latch bolt. The latch bolt 1 may also be retracted by means of an inside door handle and link (not 15 shown) connected to the latch bolt 1 at point 27.

An electromagnet 29 located below the latch bolt is fixed to the frame 3 and operates a bell crank armature 31 pivoted on a stud 33 which is fixed to the frame 3. A helical spring 35 located between the end 37 of the bell crank 31 and carried in a recess 39 in the core 41 of the electromagnet causes the end 43 of the bell crank 31 to be held downward and away from a projection 45 of the latch bolt 1 when the electromagnet is not energized.

An electrical switch 47 having a metal housing 48 is fixed to the bottom of the frame 3 and includes a movable insulating block 49 having a contact 51 fixed to its upper surface. A leaf spring 53 is located in a recess 55 in the lower surface of the block 49 which urges the block and contact 51 upward into contact with the ends of the binding posts 57 and 60 which extend through the insulated top 61 of the switch 47. 35 The circuit controlled by this switch is best shown in Figure 1. The binding post 57 is connected to one side of a source of current 58 by means of a conductor 59. The binding post 60 is connected to one end 61 of the winding of the electromagnet 29 by a conductor 63 fastened to a conductor 65. A conductor 67 also attached to the post 60 has parallel branches indicated at 69 which are connected to any number of electromagnets 29 similar to electromagnet 29 and 40 located on latch mechanisms similar to that shown in Figure 2, but which are not provided with a switch and switch operating mechanism. It is evident from the above description that if the switch block is moved to the left a connection is made between the current source to one side of each electromagnet. Two means are provided for movement of the block 49 to accomplish 45 this connection.

The movable insulating block 49 is provided 50

with an extension 71 which is slidably mounted in an opening 72 in the switch housing 48. One end of a link 73 is attached to this extension 71 and the other end 73 is bent around the upper end of a lever 77 pivoted at 79 in the frame 3. The lever 77 is operated by movement of a key and lock mechanism (not shown) located on the outside of the door. Counterclockwise movement of the lever 77 moves the switch block 49 to the left and causes the contact 51 to establish a connection between the binding posts 57 and 60. The switch block 49 may also be moved to the left by upward movement of a button 87 located on the inside of the vehicle by the following means. A clamp 79' is fixed to the link 73 by means of a screw 81 to which a Bowden wire 83 is attached. The wire 83 extends through a conduit 85 fixed to a door (not shown) and to the button 87 which is fixed to the other end of the Bowden wire. This button 87 is located inside the door.

The other end of the electromagnet winding 89 is connected to a leaf spring contact 91 by means of a screw 93. This contact 91 is attached to an insulating block 95 fixed to the frame 3. The contact extends beyond the block and bears on the surface 97 of the sector 19, and, in certain positions of the parts, on the insulating block 23 (see Figure 2). The sector 19 is grounded to the other side of the current source at 16 through the shaft 13 and frame 3, as best shown in Figure 1.

The operation is as follows: With the parts in the position shown in Figure 2, movement of the outside door handle (not shown) moves the shaft 13 counterclockwise and causes the pawl 17 to move the latch bolt 1 to the left by its contact with the projection 25. The latch bolt 1 may also be retracted by movement of the inside door handle (not shown) by means of its connection with the latch bolt at 21. To prevent retraction of any latch bolt by the outside handle, the push button 87 is either pulled upward or lever 77 is caused to be moved by the outside key (not shown), thus moving the switch block 49 to the left, as shown in Figure 3. This establishes a connection from one side of the current source to each of the electromagnets (see Figure 1). With the switch block moved to the left all latch mechanisms are set for locking. Movement of any latch to its fully retracted position is prevented by a slight movement of any door handle which completes a circuit through its respective solenoid to ground when the insulating segment 23 is moved with respect to the end of the spring contact 91 (see Figure 3). When the electromagnet 29 is energized the end 31 of the bell crank 31 is attracted to the core 41 and the end 43 moves upward about the pivot pin 33 and prevents further movement of the latch bolt by its engagement with the latch projection 45, as best shown in Figure 3.

With this coincidental locking system it is only necessary that one latch mechanism be provided with a master control switch and outside key lock for controlling any number of dependent latches located on various types of closure devices. It also provides an electrical locking system in which current is supplied only when slight pressure is applied to any outside latch retracting handle.

A modification shown in Figure 4 provides means for preventing retraction of the latch bolt by electrical and/or mechanical means. With this system each latch may be locked indi-

vidually by mechanical means or all may be set for locking from one station which is provided with an electrical switch for controlling the electrical locking means. The latch bolt 101 is slidably mounted at one end on the frame 103 in the bearing 105 and at the other end by means of a stud 107 fixed to the frame 103 and which extends through the slot 109 in the latch bolt 101. One end of a spiral spring 111 is fixed to the frame at 113 and the other end bears against a plate 115 fixed to the latch bolt 101 by means of the rivets 117 and thus serves to project the latch bolt to the right, as best seen in Figures 4 and 5.

A shaft 119 rotatable in the frame 103 has an outside door handle (not shown) attached at its outer end, and a pawl 121 with an integral downward projecting lug 123 attached at its inner end. A lever 125 is supported at one end by means of a pin 127 fixed thereto and carried in a slot 129 in the frame 103; the other end, having a pin 131 fixed to it, is slidably supported in a slot 133 in a lever 149 which will be later described. A spiral spring 135 fixed to the frame 103 at 137 has its free end 139 mounted to press against a projecting surface 141 on the lever 125 and holds it in contact with the pawl 121. Movement of the outside door handle (not shown) turns the shaft 119 in a counterclockwise direction and the pawl 121 moves the lever 125 to the left. A lug 143 on the opposite end of the lever 125 is arranged to contact a downwardly extending projection 145 on the latch bolt for retracting the bolt. The latch bolt 101 may be also retracted by an inside door handle and link (not shown) attached to the latch bolt at a point indicated at 147.

The lever 149 previously referred to is rotatably mounted on a stud 151 fixed to the frame 103. The lever 149 is provided with an arcuate slot 155 through which extends a pin 157 fixed to the frame 103. A spiral spring 153 having one end pivoted to the frame 103 and the other end pivoted to the lever 149 acts as an over center mechanism which serves to hold the lever 149 in either of its extreme positions limited by the pin 157 and slot 155. In Figure 4 the lever 149 is shown in its unlocked position.

The lever 149 extends downwardly beyond the stud 151 and is provided with a finger-shaped end 159 which projects into a recess 161 in a dog 163. This dog is formed on the end of a shaft 165 which extends through the frame 103 and arranged to be rotated by a key (not shown) from the outside.

When the dog member 163 is rotated clockwise by the outside key, the lower end 159 of the lever 149 is moved upward and the lever 125 is turned counterclockwise about the support pin 127 by the pin 131 which is carried in the slot 133 of the lever 149. This renders the pawl 121 and lug 143 ineffective for retracting the latch bolt 101. Movement of the latch bolt toward the unlatched position by means of an inside handle and link attached to point 147 causes the downwardly projecting finger 146 of the latch bolt 101 to contact the lug 143 (which is now in its lowered position) thus lifting both the lever 125 and the lever 149 and placing them in position shown in Figure 4.

Rotation of the lever 149 about the stud 151 may also be accomplished by means of an inside linkage comprising a button 167 fixed to a downwardly extending rod 169 slidably mounted in the frame 103 and provided with an inwardly turned end 171 extending through a slot 173 in the lever 149, as best shown in Figure 6. The end 171 of this link also extends through a hole 174 in the connecting link 175 which is connected by a pin 75

179 to the movable element 177 of an electrical switch shown at 178. The pin 179 extends through an insulation bushing 180 fixed to the element 177.

5 The switch 178 is provided for controlling a solenoid 181 of the master latch mechanism and also solenoids connected in parallel with the switch 178 of similar latch mechanisms. The solenoid 181 is fixed to the frame 103 above the latch bolt 101 and is provided with a movable armature 183 which is normally held in its upward position by a spring 183'. A lock bar 185 is fixed to the lower end of the armature. When the solenoid 181 is energized the armature 183 10 and the lock bar 185 are thrust downwardly so that the lock bar is in a position to contact a shoulder 102 of the latch bolt 101 as best seen in Figures 4, 5 and 8. With the lock bar 185 in this downward position full retraction of the latch bolt 101 is impossible.

15 The switch mechanism 178 is best shown in the enlarged sectional view of Figure 7. This mechanism comprises a member 177 capable of vertical displacement within a hollow casing 187 of insulating material. The member 177 is provided with contact members 189 and 191 located in a bore 193 in the lower end of the member 177. A helical spring 185 is placed between these contacts 189 and 191 and holds them outward in contact with the internal surfaces of the casing 187. The contact 189 has a rounded end which bears on the internal face 197 of a contact 199 in its extreme upward position and on the internal face 201 of the contact 199 in its extreme downward position. The contact 199 is molded in the left wall of the casing 187 and is provided with a binding post 203 fixed to its central outward extending portion 205 of the contact 199. A depression 207 located on the internal surface of the casing 187 between the ends 197 and 201 of the contact 199 serves as a detent for the movable switch element 177 when the contact 189 projects into the depression 207. This determines the mid-position of the movable switch element 177. A fixed contact 209 is provided with an integral binding post 211 which extends outward through an opening 213 in the right-hand wall of the casing 187. The contact 191 of the movable element 177 bears on the fixed contact 209 in all three positions of the movable element 177.

20 It is evident that when the movable element 177 is in either its extreme upward or downward position an electrical connection is set up between the binding posts 211 and 203. When the movable element, however, is in its mid-position, determined by the depression 207, this connection is broken.

25 The binding post 211 of the switch element 178 is connected to a source of current 213 by a conductor 215, the other side of the current source being grounded at 216 as best seen in Figure 4. The other binding post 203 is connected by means of a conductor 217 to a binding post 219 supported in an insulated strip 221 fixed to the solenoid frame 182. One end of the solenoid winding 181 indicated at 223 is connected to the binding post 219. Another conductor 225, also attached to the binding post 219, has parallel branches 227 extending to other similar solenoid windings located on other latching mechanisms controlled by the switch 178. The other end 229 of the solenoid 181 is connected to the binding post 231 also fixed to the insulating strip 221. A conductor 233 attached to the binding post 231 extends

30 downward, its lower end being attached to a spring contact 235 by a screw and nut connector indicated at 237. The spring contact 235 is supported on and insulated from a bracket 239 by means of an insulated bushing 241. The bracket 5 239 is fixed to the frame 103 by a rivet 243. It will be noted that the spring contact 235 is located adjacent to the downwardly extending lug 123 fixed to the shaft 119 to which the outside door handle is attached. When the handle is moved 10 to retract the latch the lug 123 wipes across the spring contact 235 grounding one side of the solenoid winding, the frame 103 being attached to the ground as indicated at 245.

15 All the other dependent latch mechanisms controlled by the switch 178 of the master latch mechanism shown in Figure 4 may be of the same type but are not provided with a switch mechanism. The operation of this coincidental locking system is as follows: With the parts in the 20 position shown in Figure 4 all the latch mechanisms are in the mechanically unlocked position as the lever 125 is in position to retract the latch bolt 101 but they are set for electrical locking as the inside button 167 is in its extreme upward 25 position. The movable member 177 of the switch is likewise in its extreme upward position and a connection is made from the source of current 213 to one end of each solenoid through the switch contacts 209, 191, 177, 189 and the end 30 187 of the contact 199 to which one end of each solenoid winding is connected by conductors 217, 223, 225 and 227. All the latch mechanisms are therefore set for electrically locking. If a slight pressure is applied to any door handle the shaft 35 119 will cause the lug 123 to wipe across the spring contact 235 and complete the circuit to ground through the individual solenoid winding. The current will flow from the solenoid to ground by the following conductors, namely, 229, 233, 40 contact 235, lug 123, shaft 119, thence to the frame 103 which is grounded at 245. When the solenoid winding is energized the armature 183 and lock bar 185 is thrust downward and prevents the pawl 121 from entirely retracting the 45 latch bolt 101 as the shoulder 102 then contacts the lock bar 185 preventing further movement (see Figures 5 and 8). When pressure on the door handle is removed the circuit is broken and all the parts are returned to their original position by return springs previously described. The 50 above operation applies to each dependent locking mechanism.

The latch bolt 101 may be retracted with the switch mechanism in any of its three positions 55 by moving the inside door handle and linkage which is connected to the latch bolt at 147.

Retraction of the master latch bolt by the outside door handle with the switch in this upward position can only be accomplished by the 60 door key. When the key is moved the dog member is rotated clockwise, as viewed in Figure 4, which moves the lever 149 counterclockwise about the stud 151 and thereby moves the end 171 of the rod 169 to which the inside button 167 is 65 attached downward. The switch element 177 is likewise moved downward to its mid-position by the connecting link 175 between the rod end 171 and element 177 until the circuit is broken. The key is then returned to its original position and 70 the levers 149 and 125 return to the position shown in Figure 4 so that the latch may be retracted by the outside door handle. The rod end 171 will be in the left in the mid-portion of the slot 173 of the lever 149 as shown in Figure 4. 75

the switch element will be in the mid-position, the connection between the source of current and each electromagnet will be broken and all latching mechanisms will be unlocked both mechanically and electrically.

With the parts in the position shown in Figure 4 the switch element 177 may be also moved to its mid-position by moving the inside button downward until the end 171 of the rod 169 rests in the bottom of the slot 173 in the lever 149 as best seen in Figures 6 and 7. This also corresponds to the mechanical and electrical unlocked position of the master latch mechanism.

In order to lock the master latching mechanism, both electrically and mechanically two methods may be employed. The first method is as follows: The door on which the master latching mechanism is attached is opened and the operator steps out. The inside button 167 is then fully depressed and the rod 169 and rod end 171 move the left end of the levers 149 and 125 and also the switch element 177 downward to their lowest position. This renders the lug 143 ineffective to contact the projection 145 of the latch bolt and simultaneously connects one side of each solenoid through the contacts 209 and lower end 201 of the contact 199 with the current source 213 (see Figures 4 and 7). The outside door handle is next moved in a direction to fully retract the latch bolt but as the left ends of the levers 149 and 125 are lowered the pawl 121 therefore only moves the lever 125 to the left with respect to the lever 149 until the pin 131 strikes the left end of slot 133 in the lever 149. When the door is then slammed shut the extent of the movement of the latch to the left by contacting the striker plate (not shown) is not sufficient to allow the projection 146 of the latch bolt to contact the lug 143 and move it upward. The second method of locking the master latching mechanism both electrically and mechanically is by means of the outside key. Movement of the key moves the dog 163 clockwise to its fullest extent and the right end 159 in contact with dog is moved upward about the stud 151. The left end of the lever therefore moves downward carrying both the left end of the lever 125 and switch element 177 downward in the same manner as outlined above relative to the first method of locking both mechanically and electrically. The rod end 171 will be in the upper portion of the slot 173 of the lever 149.

Unlocking is accomplished from the inside by moving the button 167 upward until the switch element is moved to its mid-position. Unlocking from the outside is accomplished by the key and dog 163. This moves the rod end 171 and switch element 177 from its lowest position to its mid-position by movement of the lever 149 clockwise about the stud 151. When the lever 149 has been moved clockwise to its fullest extent, the rod end is in the lower part of the slot 173 in the lever 149 in which position the switch element is in its mid-position and the master latch mechanism is in the unlocked position.

If the dependent latching mechanisms are similar to the one shown in Figure 4 but do not have a switch, each is mechanically unlocked when the inside button is in the upper position and mechanically locked when the button is moved to its lower position. The switch on the master mechanism sets the dependent mechanisms for locking electrically when the button is in either of its extreme positions. Electrical locking of any one dependent mechanism is ac-

complished by a slight movement of the individual door handles which energizes the respective solenoid, thus preventing retraction of the latch as described above.

In a further modification shown in Figure 9 a 5
solenoid 181' is provided for rendering the outside door handle ineffective for retracting the latch bolt 101'. The solenoid 181' is fixed to the frame 103' of a latch mechanism similar to that shown in Figure 4. All parts in Figure 9 which 10 are identical with those of Figure 4 have the same reference numbers. The armature 183' is connected to the lever 149' by the link 184'. The solenoid 181' may be connected to the master switch in the same manner as outlined in the description relative to the structures shown in Figures 1, 2 and 4 and may be used on either a master or dependent latching mechanism which has manual means or without this means for rendering the latch retracting means ineffective 20 in combination with the electrical means. With this type of mechanism any one trying to secure entry may depress the door handle fully without retracting the latch bolt and will accordingly not assume that by exerting more pressure he can gain entrance by this means. 25

I claim:

1. In a coincidental locking system comprising a plurality of closure members each having a latching mechanism including a latch bolt and latch retracting means, manually operable means for rendering the latch retracting means ineffective, electromagnetically operated mechanisms engageable with the bolts for preventing retraction of the bolts by said means, a source of current, means associated with one latching mechanism only for establishing a connection from said current source to each electromagnet, said last mentioned means being operated by the means for rendering the latch retracting means ineffective, and means associated with and operated by each latch retracting means upon movement toward unlatching position for completing a circuit through the individual electromagnets to cause the electromagnetically operating mechanism to move to engage the bolt to prevent the operation of the latch. 30 35 40 45

2. In a coincidental locking system comprising a plurality of closure members each having a latching mechanism including a latch bolt, latch retracting mechanism, electromagnetically operated mechanisms engageable with the bolts for preventing retraction by said means, a source of current, manual means comprising an inside button and an outside key mechanism, an electric switch operated by either of the manual means for establishing a connection from said source to each electromagnet in each of its extreme positions and for breaking said connection in its mid-position, and electric switch mechanisms operated by each latch retracting means for completing a circuit through the individual electromagnets to cause the electromagnetically operated mechanism to engage the bolt and prevent its retraction. 55 60 65 70 75 80 85 90 95

3. A latching mechanism for locking and unlocking a closure comprising a latch bolt, a manually rotatable pawl operated from outside said closure, shiftable means for connecting or disconnecting said pawl and said latch bolt for 70 respectively allowing or preventing retraction of said latch bolt by said pawl, a lever for shifting said shiftable connecting means, said lever being operable from inside said closure, and from outside thereof by a key, means located adj- 75

cent said latch bolt normally allowing retraction thereof but movable with respect to said latch bolt for engagement thereby to prevent retraction thereof, an electromagnet for moving said last named means, an electrical switch suitably connected to said electromagnet operated by said pawl for controlling the energization of said electromagnet, a source of electrical energy and means connecting said switch and said electromagnet with said source of energy, said means including a second switch operably connected to said lever and movable between its open and closed positions thereby.

4. In an electrically controlled latching mechanism for locking a closure comprising, a latch bolt, a retractor for the latch bolt operable from outside the closure, shiftable means for connecting and disconnecting said retractor and latch bolt, a lever for shifting said shiftable means, means located adjacent said latch bolt normally allowing retraction thereof but movable with respect to said latch bolt for engagement thereby to prevent retraction thereof, an electromagnet for moving said last named means, an electric control switch connected to said electromagnet movable to its closed position by said retractor and combined electrical and mechanical control means to allow or prevent retraction of said latch bolt comprising a master switch electrically connected to and controlling the energization and deenergization of said first named control switch and the electromagnet controlled thereby, actuating means for said master switch operable from inside said closure, said actuating means likewise being operatively connected to said lever by a lost motion connection, and outside key operated means operatively connected to said lever to move said lever and said master switch.

5. A master latching mechanism for locking and unlocking a closure and simultaneously controlling a plurality of dependent latching mechanisms, said master latching mechanism comprising, a latch bolt, a rotatable pawl manually operable from outside said closure, shiftable means for connecting and disconnecting said pawl and said latch bolt for respectively allowing or preventing retraction of said latch bolt by said pawl, a lever for shifting said shiftable connecting means, means located adjacent said latch bolt normally allowing retraction thereof said

means capable of being moved with respect to said latch bolt for engagement thereby to prevent retraction thereof, an electromagnet adapted when energized to move said last named means, an electrical switch connected to said electromagnet operated by said pawl to control energization of said electromagnet, a three position master control switch electrically connected to said electrical switch for energizing it when in its extreme positions or deenergizing said switch when in its central position therebetween and control means for said lever and said switch operably connected thereto capable of moving both to allow or prevent retraction of said latch bolt by said pawl, said means being manually operable from inside and key operated from outside said closure.

6. In a latching mechanism for a closure, a frame, a latch bolt slidable thereon, an outside retractor for the latch bolt, mechanical and electrical means for allowing or preventing retraction of said latch bolt by said outside retractor, said mechanical means comprising, a disconnectable connection between said latch bolt and said outside retractor and control means for said disconnectable connection operable from inside of said closure, and from the outside thereof by a key, said mechanical means including devices in the way of projections on the latch bolt and disconnectable connection for returning said disconnectable connection to its operative position when said closure is closed, said electrical means comprising electromagnetically actuated means adjacent said latch bolt normally allowing retraction of said bolt but movable with respect thereto for engagement by the latch bolt to prevent retraction thereof, an electromagnet for moving said last named means, control means for said electromagnet comprising an electrical switch connected to said electromagnet for controlling the energization thereof, said switch operable by said outside retractor, a source of electrical energy and means connecting said switch and electromagnet with said source of energy, said means including a master switch operably connected to said first named control means to open or close said connecting means between said source of energy and said first named switch and electromagnet.

HORACE D. SEELINGER.
